Primary Examiner — Leanne Was-Englehart(74) *Attorney, Agent, or Firm* — Berenato & White, LLC(57) **CLAIM**

The ornamental design for a door facing, as shown and described.

DESCRIPTION

FIG. 1 is a front perspective view of our design;
 FIG. 2 is a front elevational view;
 FIG. 3 is a front perspective view of a variant of FIG. 1;
 FIG. 4 is a front elevational view of FIG. 3; and,
 FIG. 5 is a fragmentary cross-sectional view taken along the line 5-5 of FIGS. 2 and 4.

The broken lines in the drawings depict environment that forms no part of the claimed design. The underlying surfaces do not form part of the claimed design.
